UNITED STATES PATENT OFFICE.

SAMUEL S. COLT, OF ORANGE, NEW JERSEY.

WEDGE.

Application filed June 20, 1924. Serial No. 721,162.

To all whom it may concern:

Be it known that I, SAMUEL S. COLT, a citizen of the United States, residing at Orange, in the county of Essex and State of New Jersey, have invented certain new and useful Improvements in Wedges; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention relates, generally, to that class of driving wedges adapted for use, more particularly, with alining elements and the holding or securing means employed with the various members of a cribbing or 20 forms used in the art of producing concrete structures.

The present invention has for its principal object to provide a novel and simply constructed, as well as an indestructible driving wedge which can be used over and over again, and which is adapted to be used in place of the usual and destructible wedge now ordinarily in use and made of wood.

The invention has for its further purpose to provide a wedge of a light structure, made of metal, but which is suitably reinforced, so as to give strength and stability to the wedge.

Other objects of the present invention not at this time more particularly enumerated will be fully understood from the following detailed description of the present invention.

With the various objects of the present invention in view, the said invention consists, primarily, in the novel wedge herein-after more fully described.

The invention is clearly illustrated in the accompanying drawings, in which:—

45 Figure 1 is a view, showing in sectional representation, fragmentary portions of a cribbing wall, a pair of stringer-elements, a portion of one of the tying members or rods extending beyond and from the outer 50 face of the cribbing wall, and having mounted thereon, and shown in side elevation, an oscillating wedge-engaging holding or tying means and a wedge employed in connection therewith, said wedge being made 55 according to and embodying the principles of the present invention; and Figure 2 is a

perspective view of the form of wedge used in connection with the various elements shown in Figure 1.

Figure 3 is a front elevation of a modified form of wedge; and Figure 4 is a vertical section of the same, said section being taken on line 4—4 in said Figure 3.

Figure 5 is a front elevation of another modified form of wedge; and Figure 6 is a vertical section of the same, said section being taken on line 6—6 in said Figure 5; Figure 7 is an elevation of still another modified form of wedge; and Figure 8 is a vertical section of the same, said section being taken on line 8—8 in said Figure 7.

Figure 9 is a front elevation, and Figure 10 is a side elevation of a form of wedge, showing another embodiment of the principles of the present invention.

Similar characters of reference are employed in all of the said herein-above described views, to indicate corresponding parts.

Referring now to the several figures of the drawings, and especially to Figure 1, the reference-character 1 indicates a fragmentary portion of one of the cribbing-walls of a mould-form of any suitable size, against the outer face of which are arranged the usual horizontal stringer-pieces or elements 2. The reference-character 3 indicates one of the usual tie-rods extending across the space of the form, from face to face, as is usual, each tie-rod having a portion 4 which projects through a hole or opening 5 in the cribbing-wall 1, said portion 4 extending between and beyond the stringer-pieces or elements 2, for the arrangement upon said projecting portion 4 of an oscillatory wedge-engaging holding or tying means 6 of any suitable construction.

One form of wedge adapted for use with the various elements hereinabove described is illustrated in Figures 1 and 2 of the drawings, the same being made of any suitable metal, and comprising a main body-portion 7 provided with an opening, as 8. Extending upwardly and forwardly from the upper solid portion 9 of the said body 7 is a member 10, which acts as a re-enforcement, and also as an anvil for the reception of the blows from the sledge or hammer of the workman when the wedge is to be driven into place.

Of course it will be evident, that with some wedges, this member 10 may be omit-

ted, if desired. The lower portions of the said body 7, adjacent the said opening 8, taper as at 11, and as shown more particularly in Figure 1 of the drawings. As shown, the long opening 8 with which the said body 7 is provided thus produces a pair of elements, in the form of legs 12 and 13, or in other words the body 7 is made yoke-shaped, so that it can be readily slipped over the tie-rod 3, as will be evident. Centrally disposed upon these legs 12 and 13, and projecting forwardly therefrom, are tapered ribs, as 14 and 15, which, as will be evident, form the wedging element of the device. Angularly shaped re-enforcing ribs 16 may also be employed, but such auxiliary ribs 16 may be omitted, as shown in the modified construction illustrated in Figures 3 and 4 of the drawings, but which latter wedge, however, is similar in its construction to the construction of the wedge represented in said Figures 1 and 2 of the drawings, and herein-above described. If desired, the wedges shown in said Figures 1 to 4 inclusive may be provided with nail or screw-receiving holes or perforations, as 17, for securing the wedges in fixed positions, against accidental displacement, after they have been driven into place.

In the modified construction of wedge illustrated in Figures 5 and 6 of the drawings, the reference-character 18 indicates the main body of the same, said body being provided with a suitably formed elongated opening 19, so as to provide an upper closed portion 20 and a lower closed portion 21. Extending upwardly and forwardly from this upper closed portion 20 is a member 22, which acts as a re-enforcement, and also as an anvil for the reception of the blows from the sledge or hammer of the workman when the wedge is driven into place.

The lower closed portion 21 of the said body 18 and the adjacent marginal portions 23 and 24, taper in a manner substantially as shown. As shown in said Figure 5, the elongated opening 19 thus also produces a pair of side-members 25, so that this form of wedge may also be used so as to straddle the tie-rod 3 in a yoke-shaped manner, similar to the construction of the wedges represented in said Figures 1 to 4 inclusive. Centrally disposed upon the said side-members 25, and projecting forwardly from each side-member, are tapered ribs, as 26 and 27, which form the wedging element of the device, as will be evident. Angularly formed marginal re-enforcing ribs 28 may also be employed, but such auxiliary ribs 28 may be omitted, if desired.

In the construction of wedge shown in Figures 7 and 8 of the drawings, the reference-character 29 indicates the main body of the wedge, the said body in this instance being provided with an elongated opening,

as 30, so as to provide the said body 29 with an upper closed portion 31, and a lower open portion 32. Directly connected with the said closed portion 31, and extending in an upward and a forward direction, 70 is a member 33, which also acts as a re-enforcement and an anvil for the reception of the blows from a sledge or hammer when the wedge is driven into place. The lower portions of the said body 29, adjacent to the 75 said opening 30, taper as at 34, and as will be evident from an inspection of said Figure 7 of the drawings. As with the construction of wedge shown in said Figures 1 to 4 inclusive, the long opening 30 with 80 which the body 29 is provided, thus produces a pair of elements, in the form of legs 35 and 36, whereby the said body 29 is also made yoke-shaped, so that it can be readily slipped over the tie-rod 3, when put in use. 85

In this case, the said body 29 and its legs 35 and 36 are respectively provided with forwardly projecting and marginally disposed tapered ribs, as 37, 38, 39 and 40, which extend entirely from the upper end 90 to the lower end of the device, substantially as shown.

In lieu of either of the forms of wedges herein-above described, I may produce a wedge, such as is represented in Figures 9 95 and 10 of the drawings.

This style of wedge comprises a main body-portion 41, preferably formed at its upper edge with an upwardly and forwardly extending member, as 42, which acts as a 100 re-enforcement and as an anvil for the reception of the blows from the sledge or hammer of the workman, when the wedge is being driven into place. The lower portion of the said body 41 tapers, as at 43, and 105 centrally disposed upon said body, and projecting forwardly therefrom, is a tapered rib 44, which forms the wedging element of the device.

One manner of using the herein-above 110 described wedges with the tying block 6, in connection with the various devices of the mold-form, will be clearly understood from an inspection of Figure 1 of the drawings, and any further description of the same is 115 deemed unnecessary. While I have constructed the herein-above described wedge for use more particularly with the members of a mold-form, as illustrated in said Figure 1, it will be understood that the wedges 120 may otherwise be used, wherever found practicable.

I am also aware, that other changes may be made in the general construction of the wedge, without departing from the scope of the present invention as set forth in the foregoing specification, and as defined in the clauses of the claims which are appended thereto. Hence, I do not limit my present invention to the exact arrangements and 125 130

combinations of the various parts as described in the said specification, nor do I confine myself to the exact details of the construction of the said parts, as illustrated in the accompanying drawings.

I claim:—

1. A wedge comprising a main body of metal and a member extending forwardly from said body, said member being provided with an angular surface tapering in a direction toward the surface of the said main body, so as to provide a wedging element for the device.
2. A wedge comprising a main body, a tapered rib extending forwardly from said body, said rib providing the wedging element of the device, and an upwardly and forwardly extending element at the upper portion of said body, said element providing an anvil.
3. A wedge comprising a main body formed with an elongated opening, and tapered ribs extending forwardly from said body on opposite sides of said opening, said ribs providing the wedging element of the device.
4. A wedge comprising a main body formed with an elongated opening, tapered ribs extending forwardly from said body on opposite sides of said opening, said ribs providing the wedging element of the device, and an upwardly and forwardly extending element at the upper portion of said body, said element providing an anvil.
5. A wedge comprising a main body formed with an elongated opening, tapered ribs extending forwardly from said body on opposite sides of said opening, said ribs providing the wedging element of the device, and angularly shaped auxiliary ribs extending forwardly from said body.
6. A wedge comprising a main body formed with an elongated opening, tapered ribs extending forwardly from said body on opposite sides of said opening, said ribs providing the wedging element of the device, and an upwardly and forwardly extending element at the upper portion of said body, said element providing an anvil.
7. In a device of the character specified, a body-portion provided upon its face with forwardly extending wedge-shaped members, and provided with a receiving opening, and an element forming part of said body, said element providing an anvil.
8. In a device of the character specified, a body-portion provided upon its face with forwardly extending wedge-shaped members, and provided with an elongated receiving opening, and an element forming part of said body, said element providing an anvil.
9. In a device of the character specified, a body-portion provided upon its face with forwardly extending wedge-shaped members, and provided with a receiving opening, and an element forming part of said body, said element providing an anvil, said body being also provided with a nail-receiving opening.
10. In a device of the character specified, a body-portion provided upon its face with forwardly extending wedge-shaped members, and provided with an elongated receiving opening, and an element forming part of said body, said element providing an anvil, said body being also provided with a nail-receiving opening.

formed with an elongated opening, tapered ribs extending forwardly from said body on opposite sides of said opening, said ribs providing the wedging element of the device, angularly shaped auxiliary ribs extending forwardly from said body, and an upwardly and forwardly extending element at the upper portion of said body, said element providing an anvil.

7. In a device of the character specified, a body-portion provided upon its face with forwardly extending wedge-shaped members, and provided with a receiving opening, and an element forming part of said body, said element providing an anvil.

8. In a device of the character specified, a body-portion provided upon its face with forwardly extending wedge-shaped members, and provided with an elongated receiving opening, and an element forming part of said body, said element providing an anvil.

9. In a device of the character specified, a body-portion provided upon its face with forwardly extending wedge-shaped members, and provided with a receiving opening, and an element forming part of said body, said element providing an anvil, said body being also provided with a nail-receiving opening.

10. In a device of the character specified, a body-portion provided upon its face with forwardly extending wedge-shaped members, and provided with an elongated receiving opening, and an element forming part of said body, said element providing an anvil, said body being also provided with a nail-receiving opening.

In testimony, that I claim the invention set forth above I have hereunto set my hand this 19th day of June 1924.

SAMUEL S. COLT.
